TONE KEYER

Philip E. Volz, Florham Park, N. J., assignor to
Radio Corporation of America, a corporation
of Delaware

Application December 14, 1950, Serial No. 200,716

15 Claims. (Cl. 250—27)

1

This invention relates to tone keyers or modulators.

A tone keyer is a device by means of which a carrier wave of tone frequency is keyed (modulated) in accordance with an intelligence wave. In any modulation system such as this, the keying frequency will tend to appear in the output, as well as the tone carrier and sideband frequencies. A desirable characteristic of such a device is the suppression or elimination of the keying frequency itself in the modulated output. If the keying frequency is eliminated, then the output consists only of the carrier frequency (tone) and its associated intelligence sidebands. When the intelligence consists of "on-off" telegraph signals (square wave keying) the linearity of the tone keyer becomes unimportant, since then it is desired to produce only 100% modulation (maximum carrier amplitude for mark and zero carrier amplitude for space).

By way of example, several rather well-known circuits operate as tone keyers. First may be mentioned the single-ended amplifier in which either the grid bias or the plate voltage is keyed. This arrangement, however, requires a high pass filter in its output, in order to suppress the keying transients. Moreover, it will give reasonable suppression of keying transients only if the carrier frequency (tone) is several times the maximum intelligence frequency.

Another type is the balanced modulator, which cancels the keying transients by adding them in phase opposition in the output. However, this requires the use of center tapped transformers having accurately balanced windings.

The ring modulator also requires the use of center tapped transformers.

An object of this invention is to provide a tone keyer which is considerably simpler than prior circuits.

An additional object is to devise a tone keyer which effectively suppresses keying transients without the use of filters.

Another object is to provide a tone keyer which requires no transformers, although these may be used if desired for D. C. isolation. However, such transformers, if used, can be relatively simple and do not need to be center tapped transformers having accurately balanced windings.

A further object is to devise a tone keyer of novel type which may be used with single-ended input and output.

Yet another object is to devise a tone keyer circuit which requires no balancing of tubes or circuit elements.

2

Still another object is to provide a tone keyer which requires no source of D. C. power, such as a D. C. anode supply.

The foregoing and other objects of the invention will be best understood from the following description of some exemplifications thereof, reference being had to the accompanying drawings, wherein:

Fig. 1 is a diagrammatic representation of a basic tone keyer circuit according to this invention;

Fig. 2 is a set of curves useful in explaining the operation of this invention;

Fig. 3 is a modified circuit arrangement; and Fig. 4 is an arrangement similar to Fig. 3 but somewhat modified.

The objects of this invention are accomplished, briefly, in the following manner: a pair of triode structures are connected in parallel with each other and this parallel combination is connected in series between a source of tone input frequency and a load resistor; the two structures are connected in reverse directions between the source and the load resistor. The keying voltage is applied cophasally to the control grids of the two triodes, keyed tone output being taken from the load resistor. In a modification, the load resistor is replaced by the primary winding of an output transformer. In a further modification, tone voltage 180 degrees out of phase with the voltage being keyed is fed to the triode output, to neutralize tone fed through the triodes during spacing intervals.

Referring to the drawings, Fig. 1 is a diagram of a basic tone keyer circuit according to this invention. An input resistor 1 is connected across a pair of tone input terminals 2 and 3, terminal 3 being grounded as shown. Terminals 2 and 3 are connected to a suitable source (not shown) 40 of voltage of tone frequency, for example, ten kilocycles. The tone input may be substantially sinusoidal, as shown in Fig. 2, line b. An output or load resistor 4 is connected across a pair of keyed tone output terminals 5 and 6, terminal 6 being grounded as shown. Thus, the tone input and keyed tone output have a common grounded terminal. Keyed tone appears across resistor 4, as will be described, and terminals 5 and 6 may be connected to any suitable load device, such as 50 a line for conveying the keyed tone to a distant point.

Two triode vacuum tube electrode structures 7 and 8 are connected in parallel and the parallel combination is connected in series between the high potential input terminal 2 and the high

potential output terminal 5. Although these vacuum tube structures are shown in separate envelopes, it will be appreciated that they can both be positioned within a single envelope, and to effect this purpose a tube of the twin-triode type, such as type 6SN7-GT, could be used for structures 7 and 8. The anode-cathode paths of structures 7 and 8 are connected reversely between input resistor 1 and output resistor 4. The anode 9 of structure 7 and the cathode 10 of structure 8 are both connected to terminal 2, while the cathode 11 of structure 7 and the anode 12 of structure 8 are both connected to terminal 5.

The control grids of structures 7 and 8 are connected together and through a resistor 13 to one terminal 14 of a pair of keying input terminals 14 and 15, terminal 15 being grounded. Thus, in Fig. 1, tone input terminal 3, keying input terminal 15 and output terminal 6 are all common and grounded. Terminals 14 and 15 are connected to be supplied with pulsating direct current energy from a suitable source (not shown), the amplitude of this pulse energy changing between a first value representing mark and a second value representing space. This change may, for example, be at a rate of 171 cycles per second. As an example, the keying voltage may be as represented in Fig. 2, line *a*, a substantially square wave with the positive excursions corresponding to mark and the negative excursions to space. For example, the keying input terminals 14 and 15 may be connected to the output of a diversity receiver of the type described in Schock et al. Patent #2,515,668, dated July 18, 1950. The output of such receiver may have the wave form illustrated in Fig. 2, line *a*.

Assume a sine wave tone input across resistor 1, as shown in Fig. 2, line *b*. The keying input voltage at terminal 14 for space interval, as shown at *d* in Fig. 2, line *a*, is made sufficiently negative to block or cut off triodes 7 and 8 throughout the entire cycle of tone input. The keyed tone output is shown in Fig. 2, line *c*. During space, both tubes 7 and 8 are cut off, so that the output is zero during this interval, as illustrated at *e* in Fig. 2, line *c*.

For mark interval, the keying input voltage at terminal 14, as shown at *f* in Fig. 2, line *a*, is made more positive than the positive peak of the tone input cycles of Fig. 2, line *b*. During a negative half cycle of tone input, structure 7 is blocked or nonconducting, since its anode 9 is then negative with respect to its cathode 11. Structure 8 conducts during this negative half cycle of tone input since its anode 12 is then positive with respect to its cathode 10. This will provide output at resistor 4. During this time of conduction triode 8 acts like a constant resistance because its grid-cathode voltage is essentially fixed due to the clamping action of a grid supply voltage *f* which is greater than the tone voltage applied to cathode 10, and also due to the series grid resistor 13. For all practical purposes the grid-cathode voltage of 8 is zero during this period. During the negative half cycles of tone input voltage occurring during mark intervals, structure 8 conducts and operates along its diode line. Then the keyed tone output voltage across resistor 4 is equal to the tone input voltage minus the diode drop in 8.

During a positive half cycle of tone input, structure 8 is blocked or nonconducting, due to a negative anode-to-cathode voltage. Structure 7 conducts during this positive half cycle of tone

input since its anode 9 is then positive with respect to its cathode 11. This will provide output at resistor 4. During this time of conduction the grid of 7 remains clamped at cathode 11. In order for the grid of 7 to remain clamped, the keying input voltage must be more positive than the cathode 11 can ever be. The maximum positive voltage that can appear at the cathode 11 is the positive peak value of the input tone, this appearing at cathode 11 when 7 conducts during positive half cycles of input tone. However, the keying input voltage at *f* is more positive than the positive peak of the tone input cycles, so that the keying input voltage is more positive than the cathode 11 can ever be. Therefore, during mark periods and during positive half cycles of tone input voltage, 7 conducts and since the keying voltage is more positive than the peak tone input voltage, the grid of 7 is clamped at (held at essentially the same potential as) cathode 11. Structure 7 is then operating along its diode line. Then the keyed tone output voltage across resistor 4 is equal to the tone input voltage minus the diode drop in 7.

It is important that the grid of whichever triode is conducting be clamped to its cathode. If the grid is clamped to its cathode the triode acts like a fixed resistance. However, if the grid is not clamped to its cathode the triode acts like a variable resistance and the output tone wave-shape will be distorted.

The keyed tone output during mark intervals such as *f* of the keying voltage is shown at *g* in Fig. 2, line *c*.

The right hand portion of Fig. 2 illustrates the operation of the circuit with the tone input removed, demonstrating the suppression of the keying frequency. It will be noted in line *b* of Fig. 2 that the tone input is zero for the right hand portion of the figure.

During the space interval the keying voltage is negative at *d'*, this negative voltage being applied to the grids of both 7 and 8. There is no current flow through the grid circuit of either triode at this time, the grids both being negative with respect to their respective cathodes, which are now substantially at ground or zero potential. Therefore, during space the output voltage is zero, as shown at *e'*.

During the mark interval the keying voltage is positive at *f'*, this positive voltage being applied to the grids of both 7 and 8. The keying voltage input applied to the grid of 7 being more positive than the cathode 11, which is now substantially at ground potential, the grid of 7 clamps at cathode 11, so that current flows through the load resistor 4, the conducting grid resistance of triode 7, and the series resistor 13 and terminal 14 back to ground 15. The voltage drop across resistor 4 gives an output voltage during this time, as illustrated at *h* in Fig. 2. Thus, as illustrated at *h* and *e'*, an output voltage of the keying frequency will appear across output terminals 5 and 6. However, this output may be made negligible by making resistor 13 very large as compared to resistor 4. In a practical circuit according to this invention, 30 to 40 db. suppression of the keying frequency is readily obtained.

Of course, when the positive mark keying voltage is applied to the grid of 8, the grid of 8 clamps at cathode 10, since cathode 10 is at ground potential when the tone input is removed. Current flows through the input resistor 1, the conducting grid resistance of triode 8 and the series resistor 13 and terminal 14 back

to ground 15. However, this current does not flow through load resistor 4 so cannot appear in the output of the circuit.

If the diode resistance of triodes 7 and 8 is small compared to the load resistance 4, amplitude distortion is negligible and inherent differences between tubes have a negligible effect. If the load impedance 4 is high compared to the tube plate resistance, then if the two tubes have different plate resistances, the percentage difference in the amplitudes of positive and negative half cycles is considerably less than the percentage difference in the plate resistances. Therefore, no balancing of tubes or circuit elements is required. Also, when each tube conducts its grid-cathode voltage is zero, due to the clamping action. This makes the tubes act like fixed resistances.

In addition, the circuit of Fig. 1 requires no transformers and has single-ended input and output, with a common terminal between tone input and keyed tone output. It will be noted that no source of D. C. power is required for the circuit of this invention, thus considerably simplifying said circuit as compared with prior circuits.

A multiple tone keyer can be made by using a multiplicity of tone keyers of the type shown in Fig. 1. The keyers would all have a common load resistor 4, but each would have a separate tone input and keying input. The multiple tone keyer would then supply the aggregate signal output of the multiplex telegraph transmitter, in the form of keyed tones.

If it is not desirable to have a common terminal for tone input and keyed tone output, as shown in Fig. 1, an input transformer and/or an output transformer may replace resistors 1 and 4. Such a circuit is shown in Fig. 3, to which reference will now be made. In this figure, elements the same as those of Fig. 1 are denoted by the same reference numerals. Tone input terminals 2 and 3' are connected to opposite ends of the primary winding 16 of an input transformer 17 to one end of the secondary 18 of which anode 9 and cathode 10 are connected. The other end of winding 18 is connected to one end of the primary winding 19 of an output transformer 20, cathode 11 and anode 12 being connected to the other end of winding 19. Output terminals 5 and 6' are connected to opposite ends of the secondary 21 of transformer 20. Thus, tone input terminals 2 and 3' and keyed tone output terminals 5 and 6' are entirely separated from each other. Winding 19 has an effective resistance which is low as compared to grid resistor 13, thus greatly reducing the keying voltage appearing in the output during mark interval, when there is no tone input. This corresponds to the relative values of resistors 4 and 13 in Fig. 1.

The keying input can also be supplied through a transformer, if it is so desired, and this feature is illustrated in Fig. 3. Keying input terminals 14 and 15' are connected to opposite ends of the primary winding 22 of a keying transformer 23 to one end of the secondary 24 of which the grids of triodes 7 and 8 are connected, through resistor 13. Since no D. C. can be coupled through transformer 23, a bias source may be needed for the grids of triodes 7 and 8. For this purpose, a biasing battery 25, poled as shown, may be connected between the remaining end of secondary winding 24 and one end of winding 18, to provide bias and to complete the keying input circuit.

to triodes 7 and 8. However, transformer coupling of a D. C. telegraph signal, as shown in Fig. 3, may not be very practical.

It will be noted that the D. C. source 25 is needed only for bias purposes. In Fig. 3, as in Fig. 1, no D. C. anode voltage is applied to the keyer triodes 7 and 8; only tone signal is applied as anode voltage.

The operation of the circuit of Fig. 3 is exactly the same as that of Fig. 1, previously described, so it will not be repeated here.

Reference will now be made to Fig. 4, which shows a modified tone keyer circuit capable of being used in an electronic multiplex telegraph transmitter of the type shown in the copending Shenk et al. application, Serial No. 211,272, filed February 16, 1951. The circuit of Fig. 4 resembles that of Fig. 3, and elements the same as those of Fig. 3 are denoted by the same reference numerals. In Fig. 4, the entire circuit operates at a potential such as 70 volts above ground, and the keying input voltage is +100 volts for mark and +15 volts for space, as indicated. The keying input is fed through a resistor 13 to the grids of the two triodes 7 and 8, as in Fig. 1.

In Fig. 4, the potential level for the entire circuit is established by connecting a point 26 to the center tap of input secondary 18 and to the end of output winding 19 which is opposite to the end to which cathode 11 and anode 12 are connected. Point 26 is the junction between two series-connected voltage dividing resistors 27 and 28 which are connected between a positive potential source of 150 volts and ground. Resistor 28 is bypassed by capacitor 29.

By analogy to Fig. 3, it may be seen that the tone voltage being keyed is provided between the center tap of winding 18 and the upper end of said winding. In the electronic multiplex transmitter of said copending application, it was required to key tones of frequencies up to 8 kc. At these frequencies the feed through of tone, from input to output, during spacing intervals, due to interelectrode capacitances in triodes 7 and 8, was more than could be tolerated. For this reason, a center tapped input transformer 17 is used to obtain a source of voltage 180° out of phase with that being keyed, to allow neutralizing of this feed through. Such an out-of-phase voltage appears at the lower end of winding 18. This out-of-phase voltage is fed through a capacitor 30 which is connected between the lower end of winding 18 and the common junction of cathode 11 and anode 12. This out-of-phase voltage, fed through capacitor 30 to the output side of triodes 7 and 8, neutralizes or balances out the tone which is fed through the interelectrode capacitances of the keyer tubes 7 and 8 when they are cut off, during spacing intervals.

Referring to Fig. 4, for a device actually constructed and satisfactorily tested, the circuit constants were as follows. These are given by way of example only since other suitably selected and properly related values may be employed.

Resistor 13	megohms	2.2
Resistor 27	ohms	150,000
Resistor 28	do	130,000
Capacitor 29	mfd	0.1
Capacitor 30	mmfd	7.5
Triode 7	6SN7-GT	1/2
Triode 8	do	1/2

What I claim to be my invention is as follows:

1. A tone keyer circuit, comprising tone input

terminals and tone output terminals, a pair of parallel-connected controllable unidirectional electron flow devices connected between the input terminals and the output terminals, said pair of devices being connected to conduct in opposite directions and each having a control electrode for control of the electron flow in the respective device, and means for applying a keying voltage to the control electrodes of said devices to control the electron flow therein.

2. A tone keyer circuit, comprising a pair of oppositely-arranged parallel-connected controllable electron flow devices each having a control electrode, means for applying tone input voltage to said devices, an output circuit connected to said devices, and means for applying a keying voltage to the control electrodes of said devices to control the electron flow therein.

3. A tone keyer circuit, comprising a pair of electron flow devices each having at least an electron-emitting electrode, an electron-receiving electrode and a control electrode, means for applying tone input voltage to the electron-receiving electrode of one device and to the electron-emitting electrode of the other device, an output impedance connected to the electron-emitting electrode of said one device and to the electron-receiving electrode of said other device, and means for applying a keying voltage cophasally to the control electrodes of both devices to control the electron flow therein.

4. A tone keyer circuit, comprising a pair of tone input terminals and a pair of tone output terminals, a pair of parallel-connected controllable unidirectional electron flow devices connected between one of the input terminals and one of the output terminals, said pair of devices being connected to conduct in opposite directions and each having a control electrode for control of the electron flow in the respective device, means connecting the remaining input terminal and the remaining output terminal both to a point of fixed reference potential, and means for applying a keying voltage to the control electrodes of said devices to control the electron flow therein.

5. A tone keyer circuit, comprising a pair of tone input terminals and a pair of tone output terminals, a pair of electron flow devices each having at least an electron-emitting electrode, an electron-receiving electrode and a control electrode, means connecting the electron-receiving electrode of one device and the electron-emitting electrode of the other device to one input terminal, means connecting the electron-emitting electrode of said one device and the electron-receiving electrode of said other device to one output terminal, means connecting the remaining input terminal and the remaining output terminal both to a point of fixed reference potential, and means for applying a keying voltage cophasally to the control electrodes of both devices to control the electron flow therein.

6. A tone keyer circuit, comprising a pair of tone input terminals and a pair of tone output terminals, means connecting said input terminals to the primary winding of an input transformer, means connecting said output terminals to the secondary winding of an output transformer, a pair of parallel-connected controllable unidirectional electron flow devices connected between one end of the secondary winding of said input transformer and one end of the primary winding of said output transformer, said pair of devices being connected to conduct in opposite directions, means connecting a spaced point on the

secondary winding of said input transformer to the remaining end of the primary winding of said output transformer, and means for applying a keying voltage to said devices to control the electron flow therein.

7. A tone keyer circuit in accordance with claim 6, wherein said spaced point is the remaining end of the input transformer secondary winding.

10. 8. A tone keyer circuit in accordance with claim 6, wherein said spaced point is an intermediate point on the input transformer secondary winding.

15. 9. A tone keyer circuit in accordance with claim 6, wherein said spaced point is an intermediate point on the input transformer secondary winding and wherein the remaining end thereof is coupled to said one end of the output transformer primary winding.

20. 10. A tone keyer circuit in accordance with claim 6, wherein said spaced point is an intermediate point on the input transformer secondary winding and wherein the remaining end thereof is coupled through a capacitor to said one end of the output transformer primary winding.

25. 11. A tone keyer circuit, comprising a pair of tone input terminals and a pair of tone output terminals, means connecting said input terminals to the primary winding of an input transformer, means connecting said output terminals to the secondary winding of an output transformer, a pair of controllable electron flow devices each having at least an electron-emitting electrode and an electron-receiving electrode, means connecting the electron-receiving electrode of one device and the electron-emitting electrode of the other device to one end of the secondary winding of said input transformer, means connecting the electron-emitting electrode of said one device and the electron-receiving electrode of said other device to one end of the primary winding of said output transformer, means connecting a spaced point on the secondary winding of said input transformer to the remaining end of the primary winding of said output transformer, and means for applying a keying voltage to said devices to control the electron flow therein.

30. 12. A tone keyer circuit, comprising a pair of tone input terminals and a pair of tone output terminals, means connecting said input terminals to the primary winding of an input transformer, means connecting said output terminals to the secondary winding of an output transformer, a pair of electron flow devices each having at least an electron-emitting electrode, an electron-receiving electrode and a control electrode, means connecting the electron-receiving electrode of one device and the electron-emitting electrode of the other device to one end of the secondary winding of said input transformer, means connecting the electron-emitting electrode of said one device and the electron-receiving electrode of said other device to one end of the primary winding of said output transformer, means connecting a spaced point on the secondary winding of said input transformer to the remaining end of the primary winding of said output transformer, and means for applying a keying voltage to said devices to control the electron flow therein.

35. 13. A tone keyer circuit, comprising a pair of tone input terminals and a pair of tone output terminals, means connecting said input terminals to the primary winding of an input transformer, means connecting said output terminals to the secondary winding of an output transformer, a pair of electron flow devices each having at least an electron-emitting electrode, an electron-receiving electrode and a control electrode, means connecting the electron-receiving electrode of one device and the electron-emitting electrode of the other device to one end of the secondary winding of said input transformer, means connecting the electron-emitting electrode of said one device and the electron-receiving electrode of said other device to one end of the primary winding of said output transformer, means connecting a spaced point on the secondary winding of said input transformer to the remaining end of the primary winding of said output transformer, and means for applying a keying voltage cophasally to the control electrodes of both devices to control the electron flow therein.

40. 14. A tone keyer circuit in accordance with claim 12, wherein said spaced point is the remaining end of the input transformer secondary winding.

45. 15. A tone keyer circuit in accordance with claim 12, wherein said spaced point is an intermediate point on the input transformer secondary winding.

50. 16. A tone keyer circuit in accordance with claim 12, wherein said spaced point is an intermediate point on the input transformer secondary winding.

55. 17. A tone keyer circuit in accordance with claim 12, wherein said spaced point is the remaining end of the input transformer secondary winding.

60. 18. A tone keyer circuit in accordance with claim 12, wherein said spaced point is an intermediate point on the input transformer secondary winding.

65. 19. A tone keyer circuit in accordance with claim 12, wherein said spaced point is the remaining end of the input transformer secondary winding.

70. 20. A tone keyer circuit in accordance with claim 12, wherein said spaced point is an intermediate point on the input transformer secondary winding.

75. 21. A tone keyer circuit in accordance with claim 12, wherein said spaced point is an intermediate point on the input transformer secondary winding.

mediate point on the input transformer secondary winding.

15. A tone keyer circuit in accordance with claim 12, wherein said spaced point is an intermediate point on the input transformer secondary winding and wherein the remaining end thereof is coupled to said one end of the output transformer primary winding.
